ABSTRACT: A dolly conveyor for a dishwasher including a table having an endless track for supporting a train of dollies for supporting dish containing baskets. The dollies abut each other and novel means is used for successively moving one dolly at a time for moving the entire train of dollies into and out from a dishwasher. The dolly moving means prevents the dollies from being moved faster than a predetermined speed through the dishwasher.

DOLLY CONVEYOR FOR A DISHWASHER

CROSS-REFERENCE TO RELATED APPLICATION

In my copending patent application on a Sectional Oval-Shaped Table for Endless Conveyor for Dishwasher, Ser. No. 632,093, filed Apr. 19, 1967, now U.S. Pat. No. 3,447,491, I disclose the type of sectional table that can be used in my present invention. The table can be made as long as desired and is preferably oval in shape although it can be of different shapes so long as it provides an endless path for the train of dish-carrying dollies to follow.

BACKGROUND OF THE INVENTION

1. Field of the Invention.

A commercial dishwashing apparatus consists of an endless track for supporting a train of dollies that carry dish-containing baskets into and out from a dishwashing machine. The dollies are interconnected by links so as to form an endless train and means is used for moving the dolly train at a predetermined speed so that the dishes will be thoroughly washed and rinsed as they pass through the dishwasher.

2. Description of the Prior Art.

The patent to Clyde R. Weihe, Jr., et al., No. 3,117,668, issued Jan. 14, 1964, is for a Conveyor For Dishwasher and discloses an oval-shaped table with dish-carrying dollies mounted thereon. Links interconnect the adjacent dollies to form an endless train and the train is mechanically moved along the table for carrying dishes into and out from a dishwasher.

SUMMARY OF THE INVENTION

An object of my invention is to provide a dolly conveyor for a dishwasher in which the adjacent dollies abut each other to form a train of dollies that will carry dishes into and out from a dishwasher. This does away with using links to interconnect adjacent dollies and permits a dolly to be removed from the train without the necessity of first freeing it from adjacent dollies.

A further object of my invention is to provide a device of the type described in which an endless chain is used for moving the train of dollies and each dolly has novel means for automatically connecting it to the continuously moving endless chain when the dolly reaches a predetermined position on the table. This novel connecting means between a dolly and the endless chain prevents the dolly from being manually moved at a faster speed than that set by the moving chain.

The endless chain is only long enough to engage one dolly at a time for moving it. When the entire table is filled with a train of dollies where all abut each other, the speed of the endless moving chain determines the speed at which the dollies carry the dishes through the dishwasher. It is possible to remove one of the dollies and thus the remaining train of dollies will be moved only when the operator manually feeds a new dolly into engagement with the chain. In this way the operator can hold up the movement of the train of dollies until he fills the basket with dishes on the dolly directly in front of him, after which he moves this dolly into engagement with the endless moving chain. The chain will then advance this dolly and all of the dollies in front of it a distance that is equivalent to the length of the dolly.

BRIEF DESCRIPTION OF THE DRAWINGS

FIG. 1 is a perspective view of the dolly conveyor when used for conveying dish-carrying baskets through a dishwasher.

FIG. 2 is a plan view of FIG. 1 and indicates the dishwashing machine diagrammatically by dash lines. A few of the dish-carrying dollies are also indicated by dash lines. The length of the oval table will be completely filled with dollies that will form a train of dollies in which adjacent dollies will abut one another.

FIG. 3 is a plan view of the oval table similar to FIG. 2, but shows one of the dollies in the train, removed from the table.

FIG. 4 is an isometric schematic view of the power section of the oval table and is an enlargement of the dot-dash oval portion shown at "FIG. 4" in FIG. 2.

FIG. 5 is an enlarged transverse section through a portion of the table and dish basket carrying dolly and is taken along the line 5-5 of FIG. 2.

FIG. 6 is another enlarged transverse section taken along the line 6-6 of FIG. 2 through the power section of the device.

FIG. 7 is a top plan view of one of the dish basket carrying dollies.

FIG. 8 is a front elevation of one of the dish basket carrying dollies and is a section through a portion of an adjacent dolly and is taken along the line 8-8 of FIG. 7.

FIG. 9 is an enlarged elevational view of one of the two drive chain engaging pawls and it is taken along the line 9-9 of FIG. 7. The pawl is shown with one of its connecting pins in engagement with a link in the endless drive chain.

FIG. 10 is a view similar to FIG. 9, but shows the pawl swung about its pivot so as to insert the locking pin in one of the drive chain links when the dolly is manually moved faster than the speed of the chain a distance sufficient to remove the drive pin of the pawl from the chain.

FIG. 11 is an enlarged elevational view of the dolly supporting wheel and shows a portion of the guide rail and is taken along the line 11-11 of FIG. 7.

FIG. 12 is a view similar to FIG. 7, but shows one of the dollies or carriers provided with a yielding tension bar and track wiper.

FIG. 13 is an enlarged section taken along the line 13-13 of FIG. 12 and shows a portion of one of the dollies and illustrates how the track wiper is operatively connected thereto.

FIG. 14 is an enlarged section of a part of FIG. 12.

DESCRIPTION OF THE PREFERRED EMBODIMENT

In carrying out my invention, I provide a table made up of sections A indicated generally in FIGS. 1, 2 and 3. The table is preferably of the type disclosed in my copending application on a Sectional Oval-Shaped Table for Endless Conveyor for Dishwasher, Ser. No. 632,093, filed Apr. 19, 1967, now U.S. Pat. No. 3,447,491. The table can be made as long as desired by simply adding sections and the sections are small enough so that they can be moved through a doorway. The joints 1 between adjacent sections are made watertight as described in my copending case.

One of the straight sections A is shown more in detail in FIG. 4. The curved sections are constructed in the same manner as the straight ones and therefore it is sufficient to state that each section A has a tongue 2 projecting from one end and it has a tongue receiving recess 3 at the other end. The tongue of one section will be removably received in the recess 3 in the adjacent section. Bolts, not shown, interconnect the adjacent sections and the joint 1, thus formed, has a nondrying waterproof mastic layer, not shown, applied between the abutting parts of both sections. If the table is to be moved to a new location, the section securing bolts can be removed to free the sections from each other and then can be reassembled at the new location. Each section A has brackets at each end that abut the brackets of adjacent sections and are connected together by the removable bolts. The brackets are not shown in FIGS. 1 to 3 inclusive because of the small scale for the drawings. The joints 1 between sections are shown.

FIG. 1 shows the table sections A, interconnected and supported by legs B. A portion of the table extends through a standard dishwashing machine indicated generally at C. This dishwasher will wash and rinse the dishes in the usual manner. After the table sections A are assembled I mount a dolly guide and supporting rail along each side of the table. This is illustrated in FIGS. 5 and 6 as well as in the assembly views of FIGS. 2 and 3. Each table section A has an inner side wall 4 that extends to a greater height than the outer side wall 5, see FIG. 4. The purpose of the higher inner wall 4 is to prevent any food particles and the like from spilling off the table while the operator is feeding dirty dish containing baskets onto the

dollies preparatory for the latter to carry the baskets through the dishwasher C for washing and rinsing the dishes and other items carried by the baskets. When the sections A form the complete oval table, the inner high wall 4 will extend throughout the length of the table. The outer wall 5 will likewise provide a lower outer wall that will extend throughout the table length.

Referring again to FIG. 4, it will be seen that I provide a side guide end supporting rail D, that is attached to the inner side wall 4. A cooperating side guide and supporting rail E is attached to the inner surface of the outer side wall 5. The rails D and E are identical to each other. They are made from stainless steel tubing that has a longitudinally extending portion forced inwardly until this inwardly bent portion contacts with the inner surface of the diametrically opposite wall portion. This is clearly illustrated in FIG. 5 and the result is that the tubular rail D, has a longitudinally extending groove 6 with a curved lower wall 6a and a curved upper wall 6b, both of which can be thoroughly cleaned because there are no square corners. Also the outer surface of the rail D, has a curved surface 7 extending from the lower wall 6a of the groove 6 to the rear surface 8 of the rail. The rail D, has another curved surface 9 extending from the upper wall 6b of the groove 6 to the same rear surface 8 of the rail. The outer surface of the rail as well as the longitudinal groove 6 are both provided with curved surfaces. This is done purposely for ease in cleaning. The other side rail E, is constructed in the same manner and similar portions will be given the same reference numerals and no further detailed description of this rail need be given.

Both side rails D and E are secured to their respective side walls 4 and 5 by the same supporting means. A description of the supporting means for the guide rail D, will suffice to include the supporting means for the rail E. An internally threaded sleeve 10, see FIG. 5, has one end welded or otherwise secured to the rear curved surface 8 of the rail D, and the axis of the sleeve lies in a horizontal plane. The inner wall 4 of the table has an opening 11 disposed the desired distance above the bottom 12 of the table section A. A stud 13 has one or more washers 14 placed on it and then the stud is inserted into the wall opening 11, after which one or more additional washers 15 are placed on the stud. The stud is then screwed into the threaded sleeve 10 and will support the rail D while spacing it the desired distance in from the wall 4.

In FIGS. 2 and 3, I show a continuous rail D secured to and spaced from the inner wall 4 of the table. I further show another continuous rail E secured to and spaced from the outer table wall 5. In actual practice, the table sections A are assembled together as indicated in FIG. 1, and then the guide and supporting rails D, and E are cut to desired lengths and secured to the table side walls 4 and 5, respectively. For example, straight lengths of rails D and E could extend throughout the straight portions of the oval table and secured to the table side walls. Then curved lengths of rails D and E could be mounted in the curved portions of the table and their ends brought into abutting arrangement with the adjacent ends of the straight rail portions. The rails D and E will extend through the length of the dishwasher C.

I will now describe the type of dolly F, I use for supporting the dish-containing baskets. FIG. 7 shows a top plan view of the dolly F and FIG. 8 is a front elevation. The dolly consists of a square frame made from stainless steel angle members. I do not wish to be confined to any particular shape for the dolly F, because it could be rectangular as well as square. The dolly frame has a rear stainless steel angle member 16 with two supporting and rear guiding wheels G, and it also has a front stainless steel angle member 17 with two additional supporting front guiding wheels H. The rear supporting and guiding wheels G for the dolly F, are placed closer together than the front wheels H because the rear wheels ride in the groove 6 of the inner guide and supporting rail D while the front wheels H ride in the groove 6 of the outer guide and supporting rail E. The curved portions for the rail D have a smaller radii from the two centers for the curved table ends than do the curved

portions for the rail E which have longer radii extending from the same two centers. It is therefore necessary that the rear wheels G be placed closer together so that they can travel around the smaller circular portions of the inner track or rail D.

Referring to FIGS. 7 and 8, it will be noted that the rear angle member 16 of the dolly F, is connected to the front angle member 17, by two side angle members 18 and 19. A side resilient bumper J is made from a stainless steel strip that has one end 20 welded or otherwise secured to the rear angle member 16 of the dolly and then the strip has a portion 21 that parallels the side 18 of the dolly and is spaced therefrom. Then the bumper strip J has an inclined portion 22 extending to the dolly side 18 with an integral portion 23 welded to the same side. The upper edge of the bumper strip J projects above the tops of the dolly frame members 16 and 18 so that the portions 20 and 23 of the bumper will also constitute retaining members for a dish-carrying basket K, shown in dash lines in FIG. 5.

Each dolly F, has two resilient bumpers secured thereto. One of them is the bumper J which has just been described and the other is a similar bumper L, see FIG. 7. Since the bumper L is like the bumper J, similar portions will be given like reference numerals except that those for the bumper L will be primed. The two resilient bumpers J and L are disposed at the corners of the dolly frame F that are the nearest to the inner wall 4 of the table. The bumpers of adjacent dollies will continuously contact each other because it is only by contact between dollies that the train of dollies is moved by the moving endless chain. The corners of the dollies disposed near to the outer wall 5 will be disposed farther apart from the similar corners of adjacent dollies as the dollies move around the curved ends of the oval table.

The upper edge of the bumper L will be spaced above the tops of the dolly frame members 16 and 19 and will hold the basket K, shown in FIG. 5, on the dolly. The inner end 24 of the bumper J is flared away from the dolly frame side 18 and the inner end 24' of the companion bumper L, is flared away from the side 19 of the same dolly so as to act as guides for the dish-carrying basket K, as the latter is manually moved onto the dolly F so as to be supported thereby.

I also provide basket retaining means on the front member 17 of the dolly F, see FIGS. 6 and 7. A strip M of stainless steel is substantially angle-shaped in cross section and it has a horizontal portion 25 overlying and welded to the top surface of the front member of the dolly F. FIG. 6 illustrates how the horizontal portion 25 has a slight raise at 25a that spaces this part above the top of the member 17 and then the strip M is bent downwardly along its entire length to provide a vertical portion 26 that extends along the front of and is welded to the dolly member 17. When the dish-carrying basket K is in proper position on the dolly F, the front lower edge of the basket will rest upon the horizontal portion 25 of the member M. The slight raise 25a in the portion 25 will prevent the basket K from accidentally slipping off from the dolly. Yet when the operator wishes to remove the basket, he can slide it forwardly so that its front edge will ride up over the slightly raised portion 25a of the member M, or he can manually lift the basket off from the dolly.

All four supporting and guiding wheels G, and H for each dolly F, are identical in construction and therefore a description of one of the rear wheels G, shown in FIG. 5, will suffice for all of the wheels. A hexagonal nut has its upper end welded to the undersurface of the horizontal portion of the rear dolly member 16. The wheel G is made up from two disc-shaped halves, a lower half 28 and an upper half 29. The two halves are provided with a central axially aligned bore that receives a bolt 30. The shank of the bolt projects above the upper disc half 29 and it is threaded to receive a lock nut 31. The lock nut cooperates with the head of the bolt 30 for clamping the two disc halves 28 and 29 together. A spacing sleeve 32 is next mounted on the bolt shank and this is followed by a washer 33. Then the projecting threaded end of the bolt 30 is screwed

into the hexagonal nut 27. A wrench, not shown, is applied to the hexagonal nut 27 to prevent it from rotating when another wrench, not shown, is applied to the head of the bolt 30 for tightening the wheel G in position on the dolly F.

Each disc half has an annular groove that cooperates with each other to form an annular groove 34 that has a wall semicircular in shape. A freely rotatable rim 35 has an inner annular groove 36 which cooperates with the annular groove 34 for receiving a plurality of balls 37, see FIG. 5. Before the disc 229 is placed on the disc 28, the rim 35 is moved into position to encircle the lower disc 28. The operator then places the desired number of balls 37 in the cooperating grooves 34 and 36, after which the upper disc 29 has its bore moved over the bolt shank and when the upper disc contacts with the lower disc, the balls 37 will be held in the groove but will be free to roll therein as the rim 35 rotates around the two stationary discs. The wheel rim 35 will ride in the groove 6 formed in the inner rail or track D.

FIG. 11 shows the front wheel H in elevation and since the structure of this wheel is identical to the wheel G shown in FIG. 5, further description of the wheel H need not be given and the same reference numerals will be applied to similar parts. The front wheels H ride in the groove of the outer rail or track E. FIGS. 2, 3 and 5, show the inner rail D, as having two recesses 38 in the upper half of the rail that are spaced the same distance apart as are the two rear wheels G, for each dolly F. This is for the purpose of allowing the operator to remove a dolly from the train of dollies if he so desires. When the two rear wheels G of the dolly are in alignment with the two recesses 38, the operator in removing the dolly from the two rails D and E, first raises the back member 16 of the dolly and this will lift the rear wheels G, and move them through the two rail recesses 38. It is then a simple matter to slide the two front dolly wheels H, out from the groove 6 in the outer rail E. The reverse procedure is followed when replacing the dolly F back into the train of dollies.

I will now describe the mechanism for moving the train of dollies F, at a predetermined speed along the table, this mechanism having novel means for preventing the speeding up of the dollies above a set speed of the chain. FIGS. 7 to 10 inclusive illustrate how two drive pawls N and P are operatively mounted on each dolly F. An elongated bracket Q is welded to the back of the rear angle member of the dolly, see FIG. 7, and this bracket has two offset portions 39 and 40 to which the pawls N and P are pivotally mounted by studs 41 and 42, respectively. The drive pawl N is of the shape shown full size by the dotted lines in FIG. 9. The pivot stud 41 is placed closer to the left hand end of the pawl so that gravity will cause the right hand end to normally rest on a stop 43 that is welded to the lower edge of the rear member 16 of the dolly F, and the bracket Q, as shown by the dot dash lines of FIG. 9. This will cause the left hand end of the pawl to extend above the upper edge of the bracket Q and this end carries an integral upstanding pin 44 that will be positioned in the path of an endless link chain R, when the dolly F is moved onto the drive section A of the table. In actual practice there will be another stop 43 provided for the other pawl 48.

The drive section A is not illustrated in FIG. 1, but it is shown in FIGS. 2, 3, 4, 9 and 10. The isometric view of FIG. 4, illustrates the inner table section wall 4 as rotatably carrying a drive sprocket 45 and an idler sprocket 46. The endless link chain R extends around both sprockets and its lower reach lies in the path the pins on the pawls N and P will take as the dollies F move along the drive section and are guided by the rails D and E. Any drive means desired may be used for rotating the drive sprocket 45. I illustrate an electric motor S for rotating the drive sprocket 45, and a variable drive connection, not shown, may be adjusted for rotating the sprocket at a desired speed. The lower reach of the endless chain R has an effective length approximately equal to the length of one of the dollies F. This will cause the drive section to positively move a dolly a distance equal to the length of the dolly. FIG. 2 shows the oval table with a train of dollies F in which each dolly has its

resilient bumpers J and L contacting with the bumpers of adjacent dollies. Therefore a positive movement of the dolly in the drive section of the table will move the entire train of dollies along the table. The pawl P of a dolly F will be the first one to be moved under the lower reach of the endless chain R. This pawl has a drive pin 47, similar to the drive pin 44 on the pawl N, see FIGS. 7 and 8, and the longer end of the pawl P, as measured from its point of pivot 42, will cause the shorter end to extend upwardly at an angle and to dispose the pin in the path of the lower reach of the chain R. The pawl P, is free to swing about its pivot and the result is that the pin 47 will enter one of the recesses in the link chain and thus be operatively connected to the chain. The chain will move the pin 47, the pawl P, and move the dolly F, the length of the lower reach.

The other pawl N is for the purpose of having its pin 44 operatively engage with the lower reach of the chain R, see FIG. 9, before the drive pin 47 on the pawl P is freed from the chain. This assures the operator that the entire length of the dolly F, is moved clear of the drive section of the table. If the table is filled with dollies, another adjacent dolly will have had its pawls N and P brought into operative engagement with the chain before the preceding dolly has been moved free of the chain. In this manner the entire train of dollies F will be kept on the move at the set speed of the chain.

Each pawl N and P, is provided with a locking pin to prevent the operator from moving the dollies manually faster than the set speed of the chain. The pawl N, has a locking pin 48 that is spaced far enough to the right of the pivot 41, see FIG. 9, that when the drive pin 44 of the same pawl is in engagement with the chain R, the locking pin 48 will be held out of engagement with the chain. The same is true of the pawl P. When the drive pin 47 of this pawl is in engagement with the chain R, the locking pin 49 on the same pawl will be out of engagement with the chain. If now the operator pushes the dolly F to the right in FIG. 9, faster than the lower reach of the chain R is moving to the right, this will cause the drive pin 44 of the pawl N to be cammed out of the chain, but before this can take place, the pawl will swing on its pivot 41 and move the locking pin 48 into engagement with the chain. It is impossible to free the drive pin 44 from the chain R before the locking pin 48 engages with the chain, see FIG. 10, where the drive pin 44 has been freed from the chain and pawl N, has swung about its pivot to insert the locking pin 48 into operative engagement with the chain. The other pawl P operates in identically the same manner as the pawl N. Before the drive pin 47 on the pawl P, see FIGS. 7 and 8, can pull free from the chain, the locking pin 49 will swing into engagement with the chain. The operator is thus prevented from moving the dolly faster than the moving chain.

OPERATION

From the foregoing description of the various parts of the device, the operation thereof may be readily understood. I have already described how the table sections A can be assembled to make a table of a desired size. FIG. 2 shows the oval table with the inner rail D secured to the high inner wall 4 and the outer rail E secured to the lower outer wall. One of the table sections A is the drive section of the type shown in FIG. 4.

The table is filled with the train of dollies F, and these abut each other and extend through the dishwashing machine C. When the motor S is started, the endless chain R will be moved at a predetermined speed and this will move the dolly F, that is in the drive section A, to the right in FIG. 2. The movement of this dolly will move the entire train of dollies. The operator would normally stand near the drive section A, and place dirty dishes in the basket on the dolly just in front of him. The dollies with their baskets are successively filled with soiled dishes and these are moved through the dishwasher at a predetermined speed where the dishes will be washed and rinsed. The clean dishes will emerge from the dishwasher and can be removed by another operator or the same operator

could load baskets of soiled dishes onto the dollies and remove baskets of cleaned dishes from the dollies after they have passed through the dishwasher.

I have already described how the pawls N and P prevent the operator from moving the dollies along the table faster than the speed of the chain. Such a movement will cause the pawls to swing about their pivots and move their lock pins 48 and 49 into operative engagement with the endless chain R so that the dolly is prevented from being manually moved faster than the chain.

In certain cases it may be desirable to intermittently feed dollies with baskets of soiled dishes into the dishwasher. There may not be a sufficient supply of soiled dishes to warrant the continuous movement of the train of dollies. The operator can remove one dolly from the train of dollies by lifting the rear wheels G of this dolly and moving them through the recesses 38 in the upper portion of the inner rail D. FIG. 3 shows the table with one dolly removed from the drive section A. Therefore the continuous movement of the endless chain R, will not move the train of dollies because there is no dolly in the drive section.

The operator can now fill the basket on the dolly next to the drive section with dishes and when this basket is filled, he can move the dolly onto the drive section. At this point the drive pin 47 on the pawl P would become engaged with the lower reach of the continuously moving chain R of the drive section and the chain would move the dolly across this section. The drive pin 44 of the other pawl N would also engage with the lower reach of the chain R, and before this pin would ride free of the chain, the dolly would have been moved free of the drive section and, of course, will have pushed all of the dollies in advance of it toward the dishwasher C. When once the dolly in the drive section has been advanced by the chain R to a point where the drive pin 44 on the pawl N, ceases to be engaged by the chain, the dolly will stop moving and all of the dollies in advance of this one will also stop moving. This permits the operator to fill the next basket on the dolly that is adjacent to the drive section, with dishes and when the basket is filled, to move this dolly into the drive section to start the next movement of the train of dollies.

FIG. 2 shows the train of dish-carrying dollies or carriers F extending around the entire oval track. As previously stated the resilient bumpers J and L, mounted on the sides of the carriers, abut the bumpers of adjacent carriers. In order to automatically take up any slight slack in the train of dollies or carriers, one or more of them is provided with a tension bar indicated generally at T, in FIG. 12. A housing 50 is welded to the side 19 of the carrier F, and encloses an end 51 of the tension bar T, as well as enclosing the portion 23' of the resilient bumper L. The end 51 of the tension bar is pivotally mounted in the housing 50 by means of a pin 52.

The tension bar T, has an inclined portion 53, see FIG. 12, that is spaced from the inclined portion 22' of the side bumper L. The tension bar T, then has a slightly curved portion 54 that is designed to yieldingly contact with the portion 21 of the adjacent side bumper J of the next dolly or carrier F. A plunger 55 is welded to the free end of the curved portion 54 and it is slidably received in a cylinder 56 that in turn is secured to the portion 20' of the bumper L. One or more coil springs 57 is mounted in the cylinder and bears against the plunger 55 for yieldingly urging it in an outward direction. An adjusting screw 58 is mounted in the wall of the housing 50 and its inner end contacts with the tension bar T. It is possible to adjust the screw 58 manually for varying the tension on the tension bar and springs 57.

When the machine is operating and the entire oval table is filled with a train of dollies or carriers F, as shown in FIG. 2, one or more of the carriers will be provided with the tension bar T. It is almost impossible to have the entire table filled with the train of dollies or carriers and have all of the side bumpers J and L contact the side bumpers of adjacent carriers without having some small space between two of the adjacent bumpers. The tension bar T is used to take up this space and it

can be swung toward or away from the adjacent bumper L by manipulating the adjusting screw 58. The cylinder 56 is shown in section in FIG. 12 so as to illustrate the one or more coil springs 57. The coil springs 57 have their ends abutting each other and they extend from the closed end of the cylinder 56 to the inner end of the plunger 55. It is possible to vary the spring tension against the tension bar T by altering the number of coil springs 57 that are disposed within the cylinder.

In FIGS. 12 and 13, I illustrate the track wiper U and show how it is supported by the dolly F. The track wiper is preferably made of rubber and it extends across the width of the table A. I prefer to mount a track wiper on every fourth dolly although I do not wish to be limited to any particular number. The track wiper is formed from a strip of rubber that is folded back on itself so as to present two resilient edges of the strip to slidably contact with the bottom 12 of the table and with the adjacent lower portions of the side walls 4 and 5 of the table. An inverted U-shaped holder 59 receives the folded portion of the wiper and a center bolt 60, see FIG. 12, secures the wiper thereto.

The front angle-shaped member 17 of the dolly frame F, and the rear angle-shaped member 16 of the same frame, see FIGS. 12 and 13, pivotally carry tubular arms 61-61. The arms have flattened ends that are pivotally connected to the frame F by bolts 62, and these ends have edges 61a that function as stops and contact with the horizontal portions of the angle-shaped members 16 and 17 when the arms extend downwardly at a predetermined angle and prevent further downward swinging. The other ends of the tubular arms are also flattened and are curved upwardly so that bolts 63 can connect them to the track wiper holder 59. The arms 61 can swing upwardly in a clockwise direction about the bolts 62 to permit the track wiper U to move up and down to follow any irregularities in the bottom 12 of the table. Since the wipers U extend from side to side of the table, their movement with the dollies will collect any foreign matter dropping onto the table and move it to a common point where it can be removed from the table.

FIG. 14 illustrates an enlarged sectional view of the cylinder 56, the plunger 55 and their associate parts. The coil springs 57 have flattened circular ends which permit the ends of adjacent springs to abut one another. The inner end of the innermost spring abuts the closed end of the cylinder 56 while the outer end of the outermost spring abuts the inner end of the plunger 55. The plunger is slidably received in the open end of the cylinder.

I claim:

1. In combination:
  - a. a dishwashing machine;
  - b. a table having an endless horizontal track with a portion extending through the dishwashing machine;
  - c. an endless train of dish basket carrying dollies all of the same size and movable along said endless track in a single horizontal plane, the adjacent dollies continuously abutting each other so that a movement of one dolly will move the entire dolly train as a unit along the endless track;
  - d. an endless chain having a portion of its length equal at least to the length of one dolly and paralleling a portion of the endless track;
  - e. a chain-engaging pawl carried by each dolly and adapted to engage with the chain portion that parallels said track when the dolly is in this portion of the track; and
  - f. means for driving said chain at a desired speed for moving the dolly whose pawl engages the chain and causing all of the train of dollies to move at the same speed as the chain.
2. The combination as set forth in claim 1 and in which:
  - a. means is automatically carried by said pawl and is engageable with said chain when any effort is made to move the dolly faster than the chain movement;
  - b. whereby said means when engaging said chain will prevent the dolly from moving faster than the chain movement.
3. The combination as set forth in claim 1 and in which:

- a. said endless track is oval shape and consists of two spaced apart endless rails that have inner and outer straight and curved portions;
  - b. each dolly including a frame with sides and inner and outer ends, the inner end of each frame supporting bumpers that continuously contact with the bumpers of adjacent dollies; and
  - c. wheels rotatably carried by the dollies and supported by the endless rails for disposing the dolly frames above the inner and outer rails, the bumpers being disposed adjacent to the portion of the frame sides that lie near the inner rail.
4. A dish basket carrying dolly comprising:
- a. a frame having side and end member;
  - b. a resilient bumper mounted on one of said end members and having a rounded corner portion disposed near each one of the two side members with straight portions that parallel the side members;
  - c. whereby when two or more dollies are arranged side by side they will have their adjacent bumpers with their straight portions abutting each other, the rounded corner portions of adjacent bumpers will contact with each other when one dolly is swung into an angular position in a certain direction with respect to an adjacent dolly.
5. A dish basket carrying dolly comprising:
- a. a frame having side and end members;
  - b. a resilient bumper mounted on each end member and having portions projecting above said frame for receiving a basket therebetween;
  - c. a bracket secured to one of said frame side members and having a portion projecting above said frame for contacting with a portion of the basket disposed adjacent thereto; and
  - d. a strip secured to the other side member and having a horizontal portion on which the adjacent portion of the basket rests, said horizontal portion extending beyond the basket with the extending part being convex in shape to prevent the basket from accidentally slipping thereover but permitting the basket to slide over the convex part when the basket is removed from the frame.
6. A dish basket carrying dolly comprising:
- a. a frame having front, rear and side members;
  - b. a tension bar carried by said frame and having a portion spaced from one of said side members;
  - c. spring means for yieldingly urging said bar portion away from said side member; and
  - d. adjustable means for spacing said bar portion at the desired distance from said side member.
7. The combination as set forth in claim 6 and in which:
- a. said spring means includes a cylinder carried by said frame and having a closed end;
  - b. a coil spring disposed in said cylinder and bearing against the closed end thereof; and
  - c. a plunger slidably received in said cylinder and having its inner end bearing against said coil spring, the outer end of said plunger being connected to said tension bar and yieldingly urging said bar portion away from said frame side.
8. The combination as set forth in claim 6 and in which a resilient bumper is mounted on said frame and is disposed on the side of said frame that is opposite to the side associated with said tension bar.
9. A dish basket carrying dolly comprising:
- a. a frame having front, rear and side members;
  - b. an arm pivotally secured to each of said front and rear frame members and being swingable in vertical planes that are parallel with these members;
  - c. a track wiper having a length substantially equal to the distance between the front and rear frame members; and
  - d. a holder for said track wiper and being connected to the free ends of said arms, the weight of the holder and track wiper tending to swing the arms downwardly about their pivots.

10. The combination as set forth in claim 9 and in which stop means is provided for limiting the downward swinging of said arms about their pivots.
11. In combination:
- a. a dishwashing machine;
  - b. a table having an endless track with a portion extending through the dishwashing machine;
  - c. an endless train of dish basket carrying dollies all of the same size and movable along said endless track, the adjacent dollies abutting each other so that a movement of one dolly will move the entire dolly train along the endless track;
  - d. an endless chain having a portion of its length equal at least to the length of one dolly and paralleling a portion of the endless track;
  - e. a chain-engaging pawl carried by each dolly and adapted to engage with the chain portion that parallels said track when the dolly is in this portion of the track;
  - f. means for driving said chain at a desired speed for moving the dolly whose pawl engages the chain and causing all of the dollies to move at the same speed as the chain;
  - g. a second chain-engaging pawl carried by each dolly and being spaced from said first-named pawl so as to engage with said chain after said first-named pawl but before said first-named pawl is freed from said chain; and
  - h. the first-named pawl on the next subsequent dolly in the train of dollies engaging with said chain just before said second pawl on the first-mentioned dolly is freed from the chain;
  - i. whereby a continuous movement of said chain will continuously move the train of dollies for moving them through said dishwashing machine.
12. The combination as set forth in claim 11 and in which:
- a. means is carried by said second pawl and is engageable with said chain when any effort is made to move the dolly, carrying said second pawl, faster than the chain movement;
  - b. whereby the means on said second pawl will prevent the dolly from moving faster than the chain.
13. A dish basket carrying dolly comprising:
- a. a frame;
  - b. means for guiding said dolly frame along a predetermined path;
  - c. an endless moving chain having a portion paralleling the dolly path;
  - d. a pawl pivotally carried by said dolly frame and adapted to follow said endless chain portion when the dolly is moved along the path;
  - e. a drive pin on the pawl and engageable with said chain for connecting the dolly to the moving chain when the dolly is in the path, whereby the chain will move the dolly along the path; and
  - f. a locking pin carried by said pawl, said locking pin engaging with said chain if the pawl is swung so as to free said drive pin from said chain.
14. The combination as set forth in claim 13 and in which:
- a. a second pawl is pivotally carried by said dolly frame and is adapted to follow said endless chain portion when said dolly is moved along the path;
  - b. a drive pin on said second pawl engageable with said chain; and
  - c. a locking pin on said second pawl and engageable with said chain if said second pawl is swung so as to free its drive pin from said chain.
15. In combination:
- a. a dishwashing machine;
  - b. a table having an endless horizontal track with a portion extending through the dishwashing machine;
  - c. a train of dish basket carrying dollies movable along said track in a single horizontal plane, the adjacent dollies abutting each other to form the train of dollies having a combined length slightly less than the length of said track;

- d. an endless chain having a portion of its length equal at least to the length of one dolly and paralleling a portion of the endless track, said chain being driven at a predetermined speed;
- e. a chain-engaging pawl carried by each dolly and adapted to engage with the chain portion that parallels said track when the dolly is in this portion of the track, the length of the dolly train being such that the space between the ends of the train is greater than the length of the chain portion

5

10

- that can be engaged by a dolly pawl; and
- f. whereby the dollies can be successively and individually fed one at a time after each has been loaded with dishes, so that the pawl on the dolly will be engaged by the moving chain and will move the dolly causing it to abut the dolly thereahead and to advance the dolly train until the chain-engaged pawl is freed from the chain portion that parallels the track.
